FLASH LIGHT

George P. Lewis, Mineola, N. Y.

Application October 24, 1957, Serial No. 48,230

Term of patent 14 years

(Cl. D48—24)

Fig. 1 is a front elevational view of a flash light embodying my new design;

Fig. 2 is a side elevational view thereof;

Fig. 3 is a bottom plan view thereof;

Fig. 4 is a top plan view thereof; and

Fig. 5 is a fragmentary sectional view taken on lines 5—5 of Fig. 2.

I claim:

The ornamental design for a flash light, substantially as shown.
